UNITED STATES PATENT OFFICE.

WILLIAM S. GODWIN, OF BALTIMORE, MARYLAND.

PAVED RAILWAY STRUCTURE AND METHOD.

Application filed January 15, 1924. Serial No. 686,275.

To all whom it may concern:

Be it known that I, WILLIAM S. GODWIN, a citizen of the United States of America, residing in the city of Baltimore, State of Maryland, have invented certain new and useful Improvements in Paved Railway Structures and Methods, of which the following is a specification.

In the construction of paved street railways, the factors to be considered are the weight and speed of the cars, the upkeep of the cars, the noise resulting from operation of the cars on the rails, cost, length of life and economy as to rails, efficiency and economical disposition of the material below the rails, resistance to the weight and impact of the traffic on the pavement, particularly heavy motor trucks, the exclusion of moisture from the structure and the efficiency and economy as to placing and life of the pavement.

The object of the invention is to produce a structure in which all these governing factors are duly provided for, so that all the features co-ordinate in the production of an improved structure and a new result in the way of efficiency and economy.

In the structure of the invention the cross tie is eliminated and the rails rest upon continuous resilient creosoted wood strips which in turn rest on continuous steel plates, or if resilience is not desired, the rails may rest directly on the plates which extend longitudinally of the track, one beneath each rail. These plates in the preferred structure are about 12 inches wide, providing an ample bearing surface, the rails and plates being embedded in the concrete.

The entire paving base or ballast is concrete laid in one solid slab. The rail and wooden strip are fixed on the plate by means of clips or in any suitable manner, the paving at the sides of the rail being preferably protected by paving guards as in my co-pending application No. 673,885.

The advantages of this structure are that the continuous support and uniform bearing thus afforded make it possible to use relatively light or shallow rails without loss of any of the desired solidity, resistance, or permanence of the structure as there is no unsupported space which must be bridged over by the rails as in the case of wooden ties where the bridged space is 12 inches or steel

plates where the space bridged over is 36 ⁵⁵ inches.

The advantages of the medium height T-rail are unquestioned. The difference in cost represents an initial saving of from 35% to 55% over the present regular practice, and the smaller T-rails are not only more economical as to first cost but more efficient. Shallow light rails have more wave motion, and therefore more tendency to creep under traffic when mounted on cross ⁶⁰ ties, but this tendency is eliminated when the rails are given a continuous bearing.

The wood cross ties which have been eliminated from the present structure, serve in the previous structures the functions of ⁷⁰ holding the rails in gauge, increasing the bearing area of the rails on the bed of broken stone, concrete or soil, and supply resilience.

In the present construction where the rail and the continuous supporting plate are permanently fixed and embedded in the concrete, there is no possibility of the track working out of gauge, and with such a bearing plate which for the average modern ⁷⁵ street railway structure may be about 12 inches wide, a concrete base 6 inches deep will withstand the heaviest traffic to which it may be subjected with an amply sufficient factor of safety, and the concrete so laid ⁸⁰ requires no reinforcing element.

Transverse members other than wooden ties have been used in some previous structures. These only serve to hold the track to gauge during the laying and setting of the ⁹⁰ concrete base. Their cost is important, running from 30¢ to 50¢ per foot of track with a correspondingly large installation cost.

In the new structure these items of expense are practically eliminated by the use ⁹⁵ of a removable gauge clamp which holds the heads of the rails to the proper spacing or gauge during the placing and setting of the concrete. In this connection it should be understood that the transverse braces formerly used serve no useful function as reinforcing, since reinforcing to be of advantage should be at the top of the slab of concrete, while these transverse members have been laid below or at the bottom of ¹⁰⁰ the rails. Also, these members engaging the bases of the rails are not as effective in setting the gauge as is the present device ¹⁰⁵

which engages the rail heads and spaces them directly where they are in turn engaged by the wheels.

The third purpose of the wooden cross ties is to provide a resilient support for the track. A resilient track is generally considered to give longer rail life, less traffic noise, less upkeep, and less rail corrugation, but it is not regarded as essential in all instances, and certain of the features of the present invention may be utilized in a rigid structure as well as in one which is resilient.

In the preferred form of the present invention continuous resilient strips of wood, which is preferably creosoted to preserve it and may to best advantage be about $\frac{5}{8}$ of an inch thick and of the width of the rail base, are provided between the rail bases and the continuous supporting plate to give a continuous and controlled resilient rail support and to keep car noise to the minimum. When rigid rails are desired the strip is omitted.

The traffic impact breaks the bond and shatters the concrete in every instance where the rails rest directly on the concrete base. This eliminates the possibility that the concrete might be considered as supporting the rails between the cross ties of wood or steel as now in use in the previous structures.

There is also a considerable saving in concrete by the elimination of wood ties and the use of a continuous plate rail support, as with this structure a continuous concrete base of uniform section is made possible, with a consequently great reduction of depth or thickness of concrete beneath the rails, whereas previously a considerable depth of concrete was necessary on account of the cutting of the base into sections or transverse strips by the ties.

An important function of the present structure is the distribution of the load over the largest practicable area of the sub-base and it is found that the continuous supporting plate structure of the present invention embedded in a concrete slab 6 inches deep below the plate is superior in its capacity for supporting traffic to a base 7 inches thick of similar material used with steel plates spaced apart. A continuous plain concrete slab 7 ft. wide and 6 inches deep below the bottom of the continuous supporting plates has been found sufficiently strong to hold any modern traffic both of electric cars and trucks. Transverse members are unnecessary and wooden ties materially weaken the concrete by dividing it transversely into strips or sections as aforesaid.

The present arrangement or structure has the further advantage that it overcomes the necessity of having one base for the track and practically another one above it for the paving near and between the tracks, the

necessary thickness of the base below the paving with the improved structure being a little over $\frac{1}{2}$ of the thickness of that used with the wooden ties.

Objections have been made to the use of monolithic paving such as asphalt and concrete adjacent the rail on account of the cost of removing and replacing it for rail joint repairs. The initial saving in the present structure is such as to pay many times over for any joint repairs which may be necessary, and the actual removal and replacement of the rails is comparatively speaking not difficult or expensive with the present structure.

An important feature of the invention resides in the method of assembling the rails and rail supporting structure. The use of actual practice of a paved street railway structure in which there are no cross ties of any sort, each rail being supported on a continuous longitudinal plate, the rail and plate being embedded in the concrete so that the rails are not only supported but maintained in gauge by the concrete, is believed to be new and to afford increased economy from various sources as already pointed out. This improved structure is made available in a practical way by applicant's improved method of construction which consists in assembling each rail with its supporting plate with or without the intermediate resilient element or wooden strip, clamping the rails together by means of a temporary gauge clamp which engages and spaces the rail heads, pouring the concrete which is to form the bed so that it is confined in a suitably shaped body around, beneath and above the supporting plates, and on both sides of the rails, permitting the concrete thus poured to become set in place, then removing the clamps and laying the paving if the roadway is to be paved.

The rails and supporting plates may be supported in the trench by means of wooden blocks or bricks and permitted to remain in the structure, or the clamps may be extended outward to each side of the bed where the clamps and rail supporting plates are supported by any suitable means, so that the entire supporting structure is removed when the concrete is set.

In the accompanying drawings I have illustrated a paved railway structure embodying my invention in the preferred form, together with the method of laying or assembling the same.

In the drawings—

Figure 1 is a transverse section through a single rail showing the rail supporting structure, a fragment of the concrete bed and paving with a wheel-tread engaging the rail.

Figure 2 is a top plan of the structure shown in Figure 1, the wheel being omitted.

Figure 3 is a longitudinal section on the line 3, 3 of Figure 1, the paving guard adjacent the plane of section being partly removed for convenience of illustration, and 5 a portion of the pavement and bed between the plane of the section, and the rail and rail supporting structure being removed.

Figure 4 is a fragmentary plan of a rail and a longitudinally extending supporting 10 plate beneath the rail to which the rail is secured, the rail being broken away intermediately to expose the longitudinal wooden strip between the rail and the supporting plate.

15 In Figure 5 I have shown a cross section of the trench which may receive and mold the bed. The section also includes the rails with the gauge clamp supporting the rails upon blocks at each side as during pouring 20 and tamping in accordance with the method of my invention.

Figure 6 is a similar section showing the rails, plates and resilient members between the rails and plates, the same being supported upon blocks in the trench which is to be occupied by the bed, the rails being spaced and held in gauge by means of a gauge clamp in accordance with a modification of my method of assembling the rails 25 and rail supporting structure.

Figure 7 is a section on the line 7, 7 in Figure 6, looking to the left.

Figure 8 is a section on the line 8, 8 in Figure 6, looking to the left in said figure.

25 Figure 9 is a section corresponding to Figure 1 but to a reduced scale and without the wooden strip.

Referring to the drawing by numerals, 40 each of which is used to indicate the same or similar parts in the different figures of the drawings,

The paved railway structure, as shown, in Figure 1 to 4, comprises the rails 1 which may be of comparatively shallow or light 45 cross-section, longitudinally extending supporting plates 3 beneath the rails, a bed of concrete 6 in which the rails and plates are embedded and in the preferred resilient structure a strip 5 of wood between the rail 50 base and the supporting plate 3.

The rails are secured by spaced U-shaped 55 clips 2, or in other suitable and convenient manner, to the longitudinally extending supporting plates 3, one of which is placed under each rail, the rails overlying the centre lines of the plates and the plates being placed continuously end to end for the full length of the rails.

The base or bottom flange 4 of the rail 60 may rest directly on the plate as in Figure 9, or there may be a layer of wood or equivalent resilient material 5 between the rail base 4 and the supporting plate, the wooden strip being comparatively thin, a strip 5/8 of an inch thick and of the width of the rail

base having been found practical in this connection, and the structure of the invention may be adapted to support a rigid track by omitting the wooden strip and placing the rail directly on the longitudinal supporting 70 plate as in Figure 9 as aforesaid.

In the resilient structure the rail and the wooden strip together are secured to the longitudinal plate 3 by means of the U-shaped clips 2, and with the rigid construction 75 the wood is omitted and the rail is secured directly to the plate by U-shaped clips which are made shorter for this purpose.

The supporting plates may to advantage be of steel about $\frac{1}{16}$ of an inch thick, 12 so inches wide and 10 ft. long, though these dimensions are merely illustrative and in no wise intended to limit the scope of the invention. The plates, as shown, are punched every few inches on each side of 85 the base, the holes 7 and 71 on the opposite sides being, as shown, in Figure 4, slightly staggered or out of alignment. Every other hole on each side of the rail is occupied by a clip 2. The intermediate holes 7' and 71' 90 provide for the admission of liquid grout which is poured and forced into the spaces which may be left under the plates 3 after tamping. When filled in this way or when properly placed and tamped, the bed affords 95 a continuous support and bearing for the plates 3.

The clips 2 have already been described as U-shaped members, it being easily understood that the cross arm 8 of the U extends 100 through the corresponding hole in the plate, that one leg of the U 9 takes over the edge of the base, and that the other leg 10 engages the plate from beneath at a point beyond the hole in the direction of the centre of the rail. It will be observed by examination of Figure 3 that the clips are reduced in cross-section intermediately of the cross arm 8 of the U, the reduction of thickness applying to the bottom leg 10 and the portion of the cross arm adjacent the same. This reduction provides shoulders 12 on each side of the clip which rest on top of the supporting plate 3, and support the clip prior to its engagement with the rail base, and the upper leg of the clamp or clip is preferably inclined at 13 to conform to the top surface of the rail base 4.

It is obvious that the clips on one side may be placed in position in the holes with the shoulders 12 resting on the plate adjacent the opening, and the rail base either with or without the wooden strip or resilient member 5 may be thrust under these clips, and that the clips on the other side of the rail base may be rocked or otherwise entered into the holes in the plate opposite the other edge of the rail base and forced home by driving wedges 14 between the outer or remote surface 15 of the respective clips, and the outer edge of the corresponding 130

openings 7 in the plate. The wedges force the adjacent clip against the edge of the rail base and force the rail into close engagement with the opposite clips so that the rails are positioned by the outside edges of the openings 71, from which they are spaced by the thickness of the clips. The clips preferably have sharp edges 72 which cut into the edge of the rail base and prevent creeping of the rails.

It is further of interest to note that the clips or at least the portion of the clips to be used on one side of the rail are preferably so formed and proportioned relatively to the opening 7, and the wedge is in turn so formed and proportioned that the thickness of the wedges in the direction at right angles to the taper, i. e., between the arrow points at 16 in Figure 1, substantially equals or exceeds the corresponding dimension of the portion of the clip at 17 which engages beneath the plate on the side of the opening adjacent the centre of the rail, and the length of the bottom leg of the U substantially equals the length of the opening 7.

The wedges 14 are preferably provided as shown with heads 18 which engage the concrete and prevent loosening of the wedges, and are convenient for engagement in removing the wedges and preferably the rails have projecting members at the side which are engaged by the concrete to prevent creeping. These may be in the form of angle irons 75, Figure 9, placed vertically and having one flange secured to the web of the rail, and the other projecting laterally into the concrete.

The rails as thus described with the longitudinal supporting plates 3 and the clips 2, and the wedges 14, including in the preferred form of the invention the resilient or wooden strip 5 between the base of the rail and the supporting plate, are when assembled as described, suitably supported in the position which they are to occupy in the finished structure, usually in a shallow broad ditch which is to contain and mold the bed of concrete by which they are held and supported in their final position. The longitudinal plates and rails may be supported by blocks of wood cut from old railroad ties or bricks or other suitable materials about which the concrete 6 is poured and which are left in the concrete bed when completed. The preferred arrangement provides for a concrete bed about 6 inches deep beneath the supporting plates and continuous in the direction of the length of the rails. This concrete bed preferably completely surrounds and encloses the longitudinal supporting plates 3 except as to the portion of the top surface thereof engaged by the rail base or the resilient strip 5, and also extends up on both sides of the rail 1 immediately adjacent the web and almost up to

the top flange from which point it is preferably inclined downwardly at 24 on each side of the rail providing for a corresponding and reverse tapering of the pavement 25 which is supported along its edges by paving guards 19 and 20, preferably spaced away from the rails, the space between the paving guards and the rails being preferably filled with asphaltic or equivalent sealing material 21 and 22 which adheres to or engages closely both the paving guards and the rails, and seals the joints, preventing seeping of water into the structure and permitting the necessary yielding and vibration of the rail without breaking the bond or destroying the sealing engagement between the filler and the paving guard on one side and the rail on the other.

The downward inclination 24 of the top surface of the concrete bed on each side of the rails and the increased thickness of the concrete bed adjacent the rail, with the consequent decrease of the thickness of the pavement 25 adjacent the rail, makes it possible to embed the rail in the concrete and at the same time reduce the total thickness of concrete. Other sources of economy resulting from this arrangement have been pointed out in the preamble. Owing to the continuous support and to the arrangement of the concrete and the reduction in the thickness of the paving adjacent the rail, a shallower rail is used than can be used in the previous structures of corresponding strength designed for similar loads, the expense of obtaining and laying cross ties is saved and also a portion of concrete, as the rails and pavement may be supported on a thinner bed of concrete owing to the continuity of the bed both vertically and longitudinally, and a structure of longer life and greater resistance is obtained at greatly reduced cost. Not only is the initial cost of construction reduced, but the cost of removing and replacing the rails is correspondingly reduced.

The arrangement and proportioning of the holes 7, the wedges 14 and the clips 2, as described, make it possible when the rails are worn or for any other reason it becomes desirable to remove and replace them or otherwise to remove them, to release the clips on the wedge side, i. e., the side of the rail on which the wedges are placed, and remove the rail by merely taking out a strip of concrete about 6 or 7 inches wide on the wedge side of the rail, removing the paving guard on that side and the corresponding portion of the paving. Under these circumstances the wedges are withdrawn, the clips on the wedge side of the rail are struck with a hammer to loosen them, and they are then moved back in their sockets, permitting the clips to be raised and removed. When the

wedges and clips on one side have been thus removed, the rails may be likewise moved to the side, disengaging them from the remaining clips and making it possible to raise them through the opening already described as formed by removing a strip of concrete.

An important feature of the invention in the way of making the improvement easily capable of practical application, resides in my improved method of assembling the structure which I have described. Wooden cross ties have, as aforesaid, been used to increase the bearing surface of the rails to lend resiliency to them and to maintain the gauge, and metal cross ties have been used to maintain the gauge and to some extent to increase the bearing surface. In my new railway structure in which the increased bearing surface is supplied by longitudinally extending supporting plates and the resiliency by longitudinal strips of wood between the rail bases and the supporting plates, there are no cross ties and the gauge is maintained by the concrete or equivalent material forming the bed in which the longitudinal supporting plates and preferably also the rails are embedded, the latter up to or almost up to the head. In some of the previous structures metal cross ties have been used which serve practically no function but maintaining the gauge, which ties are comparatively expensive to obtain and to lay. In the present instance the entire expense of cross ties is eliminated, and the rails are held in gauge until the bed is completed, by means of removable gauge clamps extending transversely and secured preferably to the heads of the rails at opposite and corresponding points. The rails and longitudinal supporting plates and resilient wooden strips assembled with the rails clamped in gauge, are supported in position during the pouring and setting of the concrete and the clamps are removed, and the supports are left in the structure or the gauge clamps themselves may be used as supports as well as to hold the track in gauge, the entire supporting structure in this instance being removed when the concrete is set.

Referring to Figures 5, 6, 7 and 8, in which the manner of assembling the structure is illustrated, I have shown in Figure 5 a combination support and gauge clamp 30 and in Figure 6 a gauge clamp 31 without the supporting feature. The gauge clamp and support 30 consists of a transverse member or rod 32 which to save weight and expense may be in the form of a pipe to which are secured two abutments 33 having outer gauge surfaces 34 spaced apart by a distance equal to the distance between the inner surfaces 35 of the rail heads when spaced according to the gauge to which the clamp is intended to relate. These abutments 33 are

shown in the form of collars on the pipe or rod 32 which may be secured in the position stated in any suitable manner, as by sweating or welding or pinning by means of pins 36 extending through the collars and through the rod or pipe 32. The gauge surface 34 referred to may be formed on the collar in any suitable manner. In the present instance it is shown as formed on an arm 37 formed integral with each collar extending a short distance on one side of the member 32 to present the gauge surface, and on the other side to a greater length forming part of a truss by which the transverse member is reinforced for the purpose of supporting the track structure during placing and setting of the concrete.

The gauge clamp further comprises hook plates 39 apertured to admit and engage the rod member 32 and to slide thereon, the hook feature being in the form of a shoulder or flange 40 at the lower edge of the plate which engages under the edge of the rail head on the outside of the rail. These plates 39 are controlled by nuts 41 engaging a suitable thread 42 on the member 32, so that the member 32 having been placed transversely of the rails which are suitably supported, the flanges or hooks 40 being placed under the edges of the rail heads as aforesaid, and the nuts 41 suitably tightened, the rails are clamped in gauge and leveled. A number of the gauge members suitably spaced and corresponding to the length of track thus clamped are employed to provide for holding the tracks or rails in gauge during placing and setting of the bed.

In the form of track support and gauge clamp illustrated in Figure 5, the transverse member 32 is extended beyond the rail clamps on each side, which extension may be in the form of separate lengths of piping 43 held in position by pipe couplings 44 which engage the members 43 and the transverse clamp member 32, the adjacent ends of both members being threaded to engage the coupling, and there is a foot or base 45 supporting each end of the gauge structure, one being secured to the outer end of each extension 43 of the member 32, and I have also shown a truss or brace 46 illustrated in the form of a small I-beam one at each side abutting at one end against the corresponding foot 45, and at the other end against the corresponding upright arm 37, the said upright arms being spaced and positioned by a compression or thrust member 47 abutting at its opposite ends against each of said members 37 respectively.

Figure 5 shows rails 1 secured to and suspended from the gauge clamp and support 30, the rails being in the position they are to occupy in the finished structure, and having longitudinal supporting plates 3 secured thereto. In order to give the clamp

a solid support, the feet 45 at each side are placed on blocks 48 which as shown rest on the soil at each side of the shallow ditch 49 which receives the concrete bed 6, part of 5 which is shown in position at the right of the figure.

In accordance with my method the rails are first secured to the clamps by the heads, the gauge surfaces 35 being placed in contact with the inner surfaces 34 of the rail heads and the nuts 41 being tightened up against the hooks 39 so that the latter are pressed against the opposite sides of the rail heads and the bends of the hooks 15 engaged with the outer bottom edges of the head. Before suspending the rails in this way, the longitudinal supporting plates 3 and strips 5 may be clamped to them, and when the rails have been placed in position as shown, supported on the gauge 20 clamps, the feet 45 of which rest on the blocks 48 at each side, the latter being suitably leveled, the concrete is poured into the ditch and tamped in over and around 25 the plates 3 and preferably against the sides of the rails 1, the top surface of the concrete adjacent the rails being given an upward inclination toward the rails and preferably meeting them near the bottom of the 30 rail head. When the concrete has set, the clamps are removed and the paving is laid over the bed.

In Figure 6 I have shown a gauge clamp without the rail supporting feature, the 35 function of this clamp being merely to hold the rails in gauge while the concrete is tamped and set. This clamp comprises a cross bar 32 having permanently secured thereto spaced abutments 50 having outwardly disposed gauge surfaces 51 for engagement with the inner surfaces of the rail heads and spaced to correspond to and with the spacing of the rail heads for the particular gauge for which the clamp is 40 to be used. The gauge also comprises movable spacing members 52 corresponding to the hooks 39 of the gauge 30, and nuts 53 by which these spacing members 52 are pressed against the outer surfaces of the 45 rail heads when the gauge clamp is in operation. Between the spacing members 52 and the nuts 53 I have shown offset hook plates 54 which are controlled by the nuts 53, and are adapted to support paving guards 19 50 beneath the edges of which the hooks engage and which are also held between the body of the hook and the spacing members 52 of the clamp.

The paving guard 19 on the outside of 60 the rail is in the form of an angle iron and may be referred to as a straight paving guard illustrated in Figures 1 and 6.

In Figure 6 I have shown a flange way paving guard 20 extending along the inside 65 edge of each rail head and supported be-

tween the abutments 50 which are the stationary gauge fixing members and hooks 59 which are suspended on the transverse gauge members 32. These hooks or hook plates 59, as shown, are apertured at 60 to receive and pass the bar 32, and may be placed on the bar by passing the bar through these apertures before placing the abutments 50 which may to the best advantage be permanently secured to the transverse rod 70 or pipe 32. The hook 59 or hook plate is preferably capable of being moved along the bar, and is, as shown, locked or fixed in position to support the paving guard by means of pins 61 which may to advantage be slightly tapered or wedge shape passed through corresponding openings 62 in the transverse member back of the guard, i. e., on the inside toward the center of the space between the rails.

In assembling or laying the rail structure in accordance with the method of my invention in the form illustrated in Figure 6, the rails 1 are first clamped to the longitudinal supporting plates 3 by means of clips 2 or in any other suitable manner, the resilient strip 5 being preferably placed between the rail base and the plate, as already described, and held between said members by the clips 2. The parts thus referred to having been assembled on the ground or in any convenient place and being as thus assembled spaced substantially to gauge are then placed in any suitable manner approximately in the position which they are to occupy and supported at exactly the right level upon blocks or other suitable supporting means 63 placed beneath the plates and spaced at considerable intervals along the rails. The gauge clamp 31 is then secured to the rail heads, the abutments 50 or more particularly the gauge surfaces 51 thereof being placed in contact with the inner surfaces of the rail heads. The outer paving guards 19 are then raised into position along the rails next to the members 52 which serve to space them from the rails providing for the admission of a suitable filler. The hook plates 54 are then placed so that they engage beneath and support the outer straight paving guards 19 and the nuts 53 are screwed up against the hook plates 54. In this connection it is noted that the flange 65 may be provided for the purpose of shielding the nut and keeping the concrete from covering and locking the same, and filling the thread immediately adjacent the nut. Tightening the nuts 53 clamps the rails.

The flange way paving guards 20 or any paving guards which may be used on the inside of the rails are then held up against the abutments 50, and the hook plates 59 are slid along the guage rod 32 until they hook under the guards which are supported 125 130

in position by hand or otherwise for this purpose, and the pins 61 are placed in the holes 62 provided for this purpose locking the hooks in engaging position.

5 The structure described having been erected in a suitable shallow ditch or mold 49 provided for the bed, the concrete or other bed material 6 is placed in position around, between and above the longitudinal 10 supporting plates 3 and preferably on both sides of the rail up to a point near the head, anchors 76 of the guards being embedded therein, and is thoroughly tamped and filled in or filled in and tamped under the 15 supporting plates 3 and around the plates and beneath the paving guards, and preferably against the rail, the portion immediately beneath the rail head being omitted to provide for the presence of a 20 filler preferably elastic and in the nature of asphalt between the guards and the head and the concrete, sealing the structure at this point and preventing seepage of water, and the concrete is preferably 25 inclined upwardly from the centre level at 66 to the base of the rail guards providing an increased thickness of concrete at the sides of the rails where shattering is apt to occur and economizing the paving 30 material at this point by giving the edges thereof a reducing taper and making it possible to use narrow or shallow paving guards further making it possible to decrease the thickness of the entire bed of 35 concrete on account of the increased supporting resistance provided adjacent the rail. The supporting blocks 63 may be permitted to remain in the structure. The concrete having set, the gauge clamps are 40 removed and the paving is laid as illustrated in Figure 1 and the filler is poured into the spaces adjacent the rail.

An important advantage of the use of the gauge clamps in this way in place of ties, 45 and in addition to the feature of economy in saving the cost of ties and of laying the same and other items above related, resides in the increased speed of construction and in the fact that the gauge clamps 50 may be applied directly to the rail heads which are the portions of the rails as to which exact placing is necessary. It is clearly apparent, in view of the disclosure, 55 that exactly the desired spacing will be more easily and cheaply obtained in this way than by setting the rails to gauge while securing the bases of the rails to wood or iron ties in accordance with the previous practice.

60 In accordance with the most approved method, the bed material, which may be concrete or other equivalent substance, is placed beneath the plates and up to the level of the plates 3 throughout the portion 65 of the bed being laid, and then tamped.

By careful placing and tamping of the material at the side of and beneath the plates, the bed may be so laid as to form a continuous and uniform support throughout the length and width of the plates, but 70 the ordinary run of labor cannot be depended upon to produce this class of work, and the bed, if carelessly laid and tamped, is apt to be formed with a hollow beneath the plates, more or less correctly represented by the dotted line 85 in Figure 1. This difficulty I have overcome, making it possible to so lay the concrete or similar bed as to afford a continuous support 75 across the entire width of the plates. This 80 is accomplished as outlined in connection with the description of the plates 3 and the holes 7, 71 on each side of the rail. In this connection I provide holes 7' 71' between each pair of the holes 7, 7 and 71, 71, 85 respectively, which receive the clips 9. These holes 7' and 71' may be shaped and placed similarly to the holes 7 and 71, the exact shape being in most instances immaterial, and they should be placed, as shown, 90 near the opposite edges of the rail base. These holes are utilized to great advantage in completing the laying of the base, liquid grout being poured through the holes 70 to 71, filling the depression or hollow 85, 95 see Figure 1, which is ordinarily left beneath the central portion of the plates after tamping.

In the practice of my method in the preferred form I find it most desirable, as 100 aforesaid, to lay a portion of the concrete forming the bed beneath the plates and up to the level of the plates on all sides. The portion of the bed thus laid is then tamped 105 on both sides of the rails and between the rails. Immediately after tamping, liquid grout is poured through the holes 7', 71', 110 entirely filling any spaces which may have been left beneath the plate, or the liquid grout or concrete may be forced through these openings 7' 71' into the spaces beneath the plate, and when the material thus inserted has hardened, which hardening 115 takes place simultaneously with the hardening of the rest of the bed beneath the plate, it presents a continuous and uniform flat surface beneath each plate upon which the plates bear, being thereby provided with a continuous and uniform support after laying and tamping the portion of the bed 120 beneath the plates and filling it if necessary.

The remainder of the bed is laid above the plates and around and between the rails, 125 practically up to a point just beneath the rail heads, as already described and illustrated, particularly in Figures 1, 5 and 6. I have thus described specifically and in detail my invention consisting of an improved railway structure and method of erecting or installing the same; however,

the specific terms herein are used descriptively rather than in a limiting sense, the scope of the invention being defined in the claims.

5. What I claim is:

1. A railway structure comprising rails, continuous longitudinal supporting plates beneath each rail, means securing the rails to the plates, and a concrete bed in which 10 the supporting plates and rails are embedded.

2. A railway structure comprising rails, continuous longitudinal supporting plates beneath the rails, means securing the rails 15 to the plates, and a concrete bed in which the supporting plates and rails are embedded, the concrete serving to hold the rails in gauge.

3. In a railway structure, rails, continuous metal supporting plates one beneath each rail extending longitudinally of the rails, means securing the rails to the plates, a continuous longitudinal strip of resilient material between each rail base, and the 25 plate, and held in position by said securing means, and a bed of concrete surrounding and substantially enclosing the plates and the strips and extending up the sides of the rails, the concrete bed being continuous and 30 of uniform transverse cross section.

4. In a railway structure, rails, continuous metal supporting plates one beneath each rail extending longitudinally of the rails, means securing the rails to the plates, 35 a continuous longitudinal strip of resilient material between each rail base, and the plate, and held in position by said securing means, and a bed of concrete surrounding and substantially enclosing the plates and 40 the strips and extending up the sides of the rails and serving to hold them in gauge.

5. The method of assembling a railway structure which consists in clamping the rail heads in gauge and supporting and 45 holding them in position, placing a base beneath the rails to support them and hold them in gauge, and removing the clamps.

6. The method of assembling a railway structure which consists in clamping the 50 rails in gauge and supporting and holding them in position, placing a base beneath the rails to support them and hold them in gauge, and removing the clamps.

7. The method of erecting a railway structure which consists in securing each rail to a separate longitudinal continuous supporting plate, clamping the rails in gauge, supporting the rails and plates in 55 position, and placing a bed of concrete around and beneath the supporting plates to support the rails and hold them in gauge, and removing the clamping means.

8. The method of erecting a railway structure which consists in securing each 60 rail to a separate continuous longitudinal

supporting plate with a continuous strip of resilient material between the rail bases and the supporting plates, clamping the rail heads in gauge by temporary means extending from one rail head to the other and 70 secured to said rail heads supporting the rails and the members secured thereto in final position, placing a bed to support the continuous plates, and removing the transverse members.

9. The method of constructing a railway structure which consists in securing separate longitudinal supporting plates to the rail bases, clamping the rails in gauge by temporary transverse members placed at intervals along the rails and secured one to each of the rails, supporting the rails and longitudinal plates thus clamped in position, placing a bed beneath and adjacent the plates to support the rails and hold them 80 in gauge, and removing the temporary transverse clamping members.

10. The combination in a railway structure of a longitudinal rail, a longitudinal plate supporting the rail and having holes 90 at the opposite edges of the rail base, U-shaped clips in said holes engaging over the rail base and beneath the plate and wedge members co-operating with the clips on one side only, forcing them against the rail and the rail against the clips on the opposite side, and a body of concrete in which the structure is embedded, said wedges having an enlarged head to be engaged by the concrete and adapted for engagement by a tool in removing the wedges.

11. A railroad structure comprising rails, a continuous plate beneath each rail, means securing the rail to the plate and a concrete bed extending around, above and beneath the plates, holding the rails in 105 gauge and in grade.

12. A railway structure comprising a rail having a head and a base, a longitudinal and continuous wooden strip beneath the rail base, a concrete bed in which the rail base and wooden strip are embedded, the concrete extending up the sides of the rail and spaced below the head, and yielding 110 filler beneath the head and between the head and the concrete.

13. In a railway structure, a rail having a head and a base, a rigid bed for the rail, wood between the rail base and the bed, the rigid bed material engaging the rail at the sides between the head and the base but spaced below the head, and bituminous material between the said rigid material and the head.

14. In a railway structure, a rail having a head and a base, a continuous longitudinal steel supporting plate secured to the rail base, a wooden cushion between the rail base and the steel plate, a concrete bed in which the plate is embedded and which 125

- extends up the side of the rail between the rail base and the head but spaced away from the head, and a yielding filler below the rail head and between the rail head and the concrete. 5
15. The combination in a railway structure of two rails each having a head and a base flange, longitudinally extending continuous plates beneath the base flange, the 10 plates having holes spaced along the edges of the base flange, clips in said holes securing the base flange to the plates, and a concrete bed beneath the plates on both sides of the plates and above the plates, affording a continuous support for the plates and holding them against lateral displacement. 15
16. The combination in a railway structure of two rails each having a head and a base flange, longitudinally extending continuous plates beneath the base flange, the plates having spaced holes along the edges of the base flange, clips in said holes securing the base flange to the plates, and a concrete bed beneath the plates on both sides of the plates and above the plates, affording a continuous support for the plates and holding them against lateral displacement, the concrete bed being continuous 20 in the direction of the length of the rails and laterally from one plate to the other. 30
17. The combination in a railway structure of two rails each having a head and a base flange, longitudinally extending continuous plates beneath the base flange, the plates having spaced holes along the edges of the base flange, clips in said holes securing the base flange to the plates, and a concrete bed beneath the plates on both sides 35 of the plates and above the plates, affording a continuous support for the plates and holding them against lateral displacement, the concrete bed being continuous in the direction of the length of the rails and laterally from one plate to the other, and resilient means between the rail bases and the plates. 40
18. In a railway structure, rails, a continuous longitudinally extending supporting plate beneath each rail, fastening means spaced at intervals along the rails, securing each rail to its continuous plate and a bed of rigid material in which the plates are embedded and which is continuous in the 45 direction of the length of the rails and transversely of the rails extending on each side of the plates, holding the plates against lateral displacement and supporting them. 50
19. In a railway structure, rails, a continuous longitudinally-extending supporting plate beneath each rail, fastening means spaced at intervals along the rails, securing each rail to its continuous plate and a bed of rigid material in which the plates 55 are embedded and which is continuous in the direction of the length of the rails and transversely of the rails extending on each side of the plates, holding the plates against lateral displacement and supporting them, resilient means between each rail and the underlying plate, the rigid material being spaced beneath the rail head and with said resilient means providing for vertical movement of the rail. 60
20. In a railway structure, rails, a continuous longitudinally-extending supporting plate beneath each rail, fastening means spaced at intervals along the rails, securing the rails to the continuous plate and a bed of rigid material in which the plates and rails are embedded and which is continuous in the direction of the length of the rails and transversely of the rails extending on each side of the plates, holding the plates against lateral displacement and supporting them, resilient means between each rail and the underlying plate, the rigid material being spaced downwardly from the rail heads and with said resilient means providing for vertical movement of the rails. 65
21. In a railway structure, a rail, a continuous longitudinally extending plate beneath the rail, clips placed at intervals along the rails, securing the latter to the plates, the clips being placed on opposite sides of the rails, an abutment on the plates for positioning each clip on one side of the rail, and a wedge co-operating with each clip on the opposite side of the rail, forcing the co-operating clips against the rail and forcing the rail against the clips on the opposite side of the rail whereby the latter clips take a bearing against the abutments and the rail is positioned by said abutments. 70
22. In a railway structure, a rail, a continuous longitudinally extending plate beneath the rail, clips placed at intervals along the rail, securing the latter to the plate, the clips being placed on opposite sides of the rails, an abutment on the plates for positioning each clip on one side of the rail, and a wedge co-operating with each clip on the opposite side of the rail, forcing the co-operating clips against the rail and forcing the rail against the clips on the opposite side of the rail and the said latter clips against the abutments, whereby the rail is positioned by said abutments, and a concrete bed in which the longitudinal plates, the 75 clips and the wedges are embedded. 80
23. In a railway structure, a rail, a continuous longitudinally extending plate beneath the rail, clips placed at intervals along the rail, securing the latter to the plate, the clips being placed on opposite sides of the rails, an abutment on the plates for positioning each clip on one side of the rail, and a wedge co-operating with the clips on the other side of the rail and forc- 85

ing the rail against the clips on the abutment side of the rail whereby the rail is positioned by said abutments, and a concrete bed in which the longitudinal plates, 5 the clips and the wedges are embedded, the thickness of each wedge being substantially equal to the width of the engaging surface of the co-operating clip so that the clips controlled by the wedges may be released by removing the concrete on that 10 side of the rail and removing the wedges, and without disturbing the concrete beneath the plate.

24. The combination in a railway structure of rails, a longitudinally extending continuous plate beneath each rail, the plate having holes spaced along each side of the rail, clips in said holes, securing the rail to the plate, the holes on one side of 15 the rail having an excess width, and a wedge co-operating with each clip in the larger openings only, forcing the clips against the rails and forcing the rails against the clips on the opposite side of the rails the latter clips taking a bearing against the edges 20 of the corresponding holes in the plates.

25. The combination in a railway structure of rails, a longitudinally extending continuous plate beneath each rail, the plate 30 having holes spaced along each side of the rail, clips in said holes, securing the rail to the plate, but holes on one side of the rail having an excess width, and a wedge co-operating with each clip in said larger 35 openings, forcing the clips against the rail and forcing the rails against the clips on the opposite side of the rail, the thickness of each wedge approximating the corresponding dimension of the engaging surface of the clip with which it co-operates, a concrete bed in which the plates and clips and a portion of each rail are embedded, the arrangement of the clips making it possible to remove the clips on one side and 40 release the rail by removing the concrete on the wedge side of the rail and removing the wedges, thereby releasing the clips on that side and removing them without disturbing the concrete beneath the plate, 45 whereby the rail may be moved to the corresponding side and removed.

26. The method of laying a paved railway structure which consists in clamping the rails to each other according to the desired 55 gauge by means of temporary transverse members extending from one rail to the other, and clamping paving guards to said transverse members on each side of the rail, supporting the paving guards and rails thus 60 clamped in the final position which they are to occupy, placing a concrete bed around, beneath and between the rails, portions of the guards being also embedded in the concrete, permitting the concrete to harden 65 so that it supports the rails and holds them

in gauge and supports the paving guards, removing the clamping members, laying a pavement on the bed.

27. The method of laying a paved railway structure which consists in clamping the rails to each other according to the desired gauge by means of temporary transverse members extending from one rail to the other, and clamping paving guards to said transverse members on each side of the rail, 70 supporting the paving guards and rails thus clamped in the final position which they are to occupy, placing a concrete bed around, beneath and between the rails, portions of the guards being also embedded in the concrete, permitting the concrete to harden so that it supports the rails and holds them in gauge and supports the paving guards, removing the clamping members, laying a 75 pavement on the bed and up to and against the paving guards, and sealing the space between the paving guards and the rails, which members are spaced slightly apart to admit the sealing material.

28. The method of laying a paved railway structure which consists in securing a longitudinally extending continuous supporting plate to the base of each rail with a resilient member between the rail base and the plate, securing the rails to each other in the desired gauge by means of temporary clamping members, securing paving guards on each side of the rail and spaced therefrom supporting the rails thus clamped in the final position, placing a bed of plastic 90 around and beneath the plates and above the plates on each side of each rail, the same being spaced slightly below the rail head and having embedded therein a portion of the rail guards, laying a pavement on the bed, and filling the space between the paving guards and the rails, and between the rail heads and the bed with a relatively 95 soft filling material.

29. The method of laying a railway structure which consists in securing each rail to a continuous longitudinally supporting plate, clamping the rails in gauge by temporary means, extending from one rail to the other, holding the rails and the supporting plates in final position, and laying a bed of plastic around and beneath the plates, extending continuously along the plates and from one plate to the other and beyond the plates on the outsides thereof, permitting 100 the bed to set, and removing the clamps.

30. A railway structure comprising rails, a continuous plate beneath each rail, means securing the rail to the plate, a concrete bed extending around, above and beneath the plates, the rails being partially embedded therein and being provided with members placed at intervals and projecting laterally into the concrete to prevent creeping 105 of the rails.

31. A railway structure comprising rails, and the other flange projecting laterally a continuous plate beneath each rail, means 35
securing the rails to the plates, a concrete bed extending around, above and beneath 5
the plates, the rails being partially embedded therein and being provided with members placed at intervals along the rail and projecting laterally from the web of the rail into the concrete to prevent creeping of 10
the rails.
32. A railway structure comprising rails, a continuous plate beneath each rail, means 15
securing the rails to the plates, the concrete bed extending around, above and beneath 15
the plates, the rails being partially embedded therein and being provided with members placed at intervals along the rails and projecting laterally from the webs of 20
the rails into the concrete to prevent creeping of the rails, said members being separate pieces secured to the rails.
33. A railway structure comprising rails, a continuous plate beneath each rail, means 25
securing the rails to the plates, a concrete bed extending around, above and beneath 25
the plates, the rails being partially embedded therein and being provided with members placed at intervals along the rails and projecting laterally from the webs of 30
the rails into the concrete to prevent creeping of the rails, said members being in the form of angle irons extending in a vertical direction, having one flange secured to the web
34. The combination with a tamped road-bed of a longitudinal supporting plate for a railway rail, means for fastening a rail to the plate and apertures in the plate at the sides of the rail through which cement 40 40
may be poured to supplement the tamping of the bed and to give a continuous bearing for the plate, said apertures being open when the rail is fastened to the plate.
35. The method of laying a railway structure which consists in securing a longitudinally extending continuous supporting plate to the base of each rail, supporting the rails and plates in final position, laying and tamping a bed beneath and at the sides of 45 50
and between the plates, and introducing a soft plastic into the spaces which may be left beneath the plates.
36. The method of constructing a railroad which consists in securing each rail to a longitudinal supporting plate, leaving apertures at the sides of the rails, supporting the rails and plates with the rails in gauge and in final position, placing a bed of plastic material beneath and between the plates and 55 60
on both sides of the plates, and introducing a plastic through the openings in the plates into the spaces beneath the plates.

Signed by me at Baltimore, Maryland,
this 11th day of January, 1924.

WILLIAM S. GODWIN.
